UNITED STATES PATENT OFFICE.

EDWARD CLIFTON NEWTON, OF RENO, NEVADA, ASSIGNOR OF ONE-HALF
TO WILLIAM PICKERSGILL, OF RENO, NEVADA.

SWITCH FOR OVERHEAD RAILWAYS.

No. 848,681.

Specification of Letters Patent.

Patented April 2, 1907.

Application filed February 6, 1907. Serial No. 356,069.

To all whom it may concern:

Be it known that I, EDWARD CLIFTON NEWTON, a citizen of the United States, and a resident of Reno, Washoe county, Nevada, 5 have invented certain new and useful Improvements in Switches for Overhead Railways, of which the following is a specification.

My invention relates to that class of apparatus in which a carrier travels upon overhead rails supported by pendent brackets, and relates to the switch device of such an apparatus whereby the carrier may be deflected from the main rail to any one of a series of radiating rails; and my invention 15 consists of means whereby the switch may be readily supported and carried to different positions and automatically locked there without lost motion until it is necessary to change the position, as fully set forth hereinabove and as illustrated in the accompanying drawings, in which—

Figure 1 is a perspective view illustrating a part of an overhead railway and embodying my improvements. Fig. 2 is a section showing part of the switch-plate and carrier and locking device. Fig. 3 is a section 25 through the carrier and switch-plate. Fig. 4 is a transverse section illustrating a different arrangement of the locking device. Fig. 5 is a transverse section illustrating a different 30 arrangement of the locking device and different form of guide and carrier.

The switch-plate A is adapted for attachment beneath any suitable support and supports a series of pendent hangers D, adapted 35 for the attachment of a series of radiating rails J, and a hanger F, also adapted for attachment to and below any suitable support, supports the end of the main rail G, to which 40 is pivoted at x the switch-rail E, the latter being connected at its outer end to the bracket 1 of a carrier C, which slides upon and is supported by a guide on the switch-plate. The hangers D are arranged upon a curve, and the 45 guide is also upon a curve concentric with a circle the center of which is the pivotal point x of the switch, so that the swinging end of the switch E may be brought opposite the end of either one of the radiating rails J, supported 50 by the hangers D, to permit the roller or wheel y of the carrier X to pass over the switch onto any one of the diverging tracks.

In order to insure the absolute coincidence

of the end of the switch-rail with the end of the radiating rail on the edge of which the 55 carrier should pass, I provide an automatic lock L of any suitable character which will hold the carrier C in its proper position after adjustment. As shown, the lock is in the form of a rounded bolt 3, adapted to a series 60 of notches or recesses 4. In Figs. 1, 2, and 3 these recesses are shown as in the switch-plate. In Fig. 4 they are in one of the edges of the guide. In Fig. 5 they are in the hangers; but whatever their position the 65 bolt will spring into place in the notch whenever it is brought opposite the same, with the end of the switch opposite the end of the radiating rail. According to the position of the notches the bolt may be carried by the 70 carrier C in a vertical position, as in Figs. 1, 2, and 3, or in a horizontal position, as in Figs. 4 and 5. As best shown in Fig. 2, the bolt has a stem fitting a spring 5 of pure gum 75 confined in a casing 6, adapted to a socket in the carrier and confined in place by a screw-plug 7; but of course a spiral spring or other suitable character of spring-bolt could be operated with like effect.

In the construction shown in Figs. 1 to 3 80 the notches 4 have sides at right angles to each other, and as the switch-rail is supported by the bracket 1 at a considerable distance below the carrier C any pressure tending to deflect the switch-rail out of line with 85 the rail J would have but very little effect to force the bolt against the inclined sides of the notches and carry the bolt inward, so that the lock is effective in holding the parts in place; but by applying sufficient draft to the 90 carrier itself the bolt may be forced inward, so as to permit the carrier to be shifted from one position to the other, the bolt springing outward and tending to lock the carrier whenever it is brought opposite any one of 95 the notches. Different means may be employed for shifting the carrier. As shown, it is provided with eyes adapted for attachment with drag-chains 88.

The guide for the carrier may be differently 100 constructed. As shown in Figs. 1 to 4, it consists of two separated flanged ribs, upon which the carrier slides, with the hanger or bracket between. In Fig. 5 there is a single flanged rib adapted to a corresponding socket 105 in the carrier.

As shown, the hangers D are connected detachably with the switch-plate, the latter having a series of openings 2, adapted to receive the bolts by which the hangers are secured.

Without limiting myself to the precise construction and arrangement of parts shown,

I claim—

1. In a switch device for elevated rails, a switch-plate provided with a series of hangers and with a guide arranged on parallel curves, a second bracket for supporting the main rail, a switch hinged to the main rail, a carrier adapted to slide upon the guide of the switch-plate and to support the outer end of the switch, and a spring-lock carried by the carrier and adapted to engage notches upon the switch-plate, or parts supported thereby, for the purpose set forth.
2. The combination with a switch-plate having a curved guide and a series of hangers, of a carrier movable upon the said guide and adapted to support the end of a switch, and provided with a spring-lock, for the purpose described.

3. The combination of a switch-plate and series of hangers connected thereto in position to support a series of radiating rails, and with a curved guide and series of notches,

and a carrier sliding upon said guide and provided with a lock for engaging said notches, and having a bracket adapted to support the end of a pivoted switch.

4. The combination of a switch-plate and series of hangers supported thereby, a curved guide consisting of separated flanged ribs and series of notches in the switch-plate, a carrier sliding upon said guides and provided with a hanger or bracket extending downward between the guides, and a spring-lock carried by the carrier and adapted to notches in the switch-plate.

5. The combination of a switch-plate, pendent hangers and means for connecting the hangers detachably to the plate, a curved guide upon the switch-plate, a slide supported by said guide and provided with a bracket for the attachment of a switch, and a spring-lock provided with a rounded bolt, and carried by the carrier and adapted to engage notches in the switch-plate.

In testimony whereof I affix my signature in presence of two witnesses.

EDWARD CLIFTON NEWTON.
